JOSEPH GRUBER, OF SIOUX FALLS, SOUTH DAKOTA.

HEATER AND PURIFIER.

Application filed December 7, 1925. Serial No. 73,572.

The invention relates to improvements in heaters and purifiers of lubricating oil for internal combustion engines.

One of the objects of the invention is to remove deleterious liquids from lubricating oil, thereby to improve its depreciated quality and to restore it to its pristine usefulness.

Another object is to decrease the viscosity of lubricating oil in cold weather by heating it to render it sufficiently mobile for lubricating purposes.

Another object is to provide means to volatilize the gaseous and vaporous constituents of the adulterate lubricating body and carrying them away and utilizing them in the cylinder of the engine.

A further object is to expedite the extraction of the gaseous and vaporous products by confining bodies of said oil in a chamber under sub-atmospheric pressure, and a further refinement consists in constantly changing the components of the entire body by producing a continual circulation of oil thru said chamber until a relatively larger supply of oil has been treated.

Other and further objects, advantages and benefits of the invention will readily appear from a consideration of the following description and drawings forming a part hereof, wherein:

On the drawings:

Figure 1 is a side elevation of an internal combustion engine showing the device attached thereto;

Fig. 2 is an enlarged, central, vertical section thru the heater;

Fig. 3 shows a similar section at right angles thereto;

Fig. 4 is a transverse section taken substantially on line IV—IV of Figure 3;

Fig. 5 is a bottom plan view of the heater; and

Fig. 6 is a section thru a check valve used to control the attenuation of gases or vapors in the upper part of the structure or heater.

In all of the views the same reference characters are used to indicate similar parts.

As shown on the drawings:

Showing an exemplification of my invention, 10 is a typical internal combustion engine having a crank case 11 containing a supply of lubricating oil 12.

The accessory, embodying the invention, includes a casing 13 connected to the bottom part of the crank case 11 by a flanged in-

tegral tube 14 (Fig. 3) allowing free passage of oil from the crank case into the casing 13. The oil level 15 is always below the top wall 16 of the casing, to leave a space 17 above the oil in the casing 13.

This space is connected by a small tube 18 to the intake manifold 19 of the engine 10. A pipe 20 passes thru the casing 13 in a generally axial direction and terminates in a perforated end 21. The upper end 22 of the pipe 20 is connected to the exhaust pipe 23 of the engine 10. A butterfly valve, or damper 24, may be placed in the exhaust pipe 23 between the pipe 20 and the terminal end of the pipe 23 which may be moved by lever 25 to vary the choke effect thereof, for the purpose of regulating the temperature of the oil 12 in the casing 10 in an obvious manner.

A sufficient quantity of the hot products of combustion should be diverted from pipe 23 thru pipe 20 to heat the contents 12 of the casing 10 to a temperature above the vaporizing point of water but not sufficiently to cause ebullition of the oil.

The involved gases and vapors will rise into the space 17 above the oil content and will be drawn into the cylinders of the engine thru the tube 18, at the same time a sub-atmospheric pressure is thus maintained in the space 17 therefore volatilization of the more readily vaporizable liquid contents is more easily effected.

When lubricating oil in an internal combustion engine becomes substantially gelatinized by effect of very low temperature, it loses its lubricating qualities, because of its lack of mobility and is no longer useful for such purpose. The damp air in the crank case becomes condensed and the water of condensation mixes with the oil forming an emulsion and raises its freezing point.

Gasoline from the combustion chambers of the engine leaks by the pistons into the crank case and dilutes the oil, all of which effects depreciate the oil as a lubricating agent and all of the causes of these ill effects may be removed or eliminated by operation of my device.

Applicant realizes that means for heating lubricating oil of an engine have heretofore been suggested, but in all such devices with which he is acquainted the more readily, volatilizable dilutant liquids have not been removed from the oil when the temperature of the mixture has been raised suf-

ficiently to convert them into vapors and gases.

Near the bottom of a casing 13, a tube 26 is connected to a discharge opening 27.

5 Oil passes thru strainer 28 into the tube 26 and thru it to the intake of an oil pump 29.

From the discharge of the oil pump 29 a tube 30 leads back into the crank case 11. By this means oil is kept in constant circulation from the crank case thru the oil purifier 13. Another pipe 31 may lead to other 10 bearings requiring lubrication when the stop-cock 32 is open.

I may place a safety valve 33 in the upper 15 part of the casing to vent the space 17 in event of too great exhaustion of the space 17.

The device may take other forms than that shown without departing from the spirit of the invention and there will necessarily be some modifications required to meet 20 the individual peculiarities of different types of automobiles.

To meet these conditions is well within the knowledge of the artisan versed in the art.

25

I claim is my invention:

A device of the character described comprising a closed casing, a pipe extending thru the casing thru which to pass hot gases to heat the contents of the casing, an oil inlet near the bottom of the casing for connection to the crank case of an engine, an opening at the upper end of the casing for a tube to connect it to the intake conduit of an engine, a discharge opening near the bottom of the casing for connection of an oil circulating tube, an oil strainer in the casing overlying the latter opening, and a spring pressed valve connected to the upper end of the casing for opening inwardly of the casing.

30 35 40 In testimony whereof I have hereunto subscribed my name.

JOSEPH GRUBER.
